[57] CLAIM

The ornamental design for a charger stand for a portable handset telephone and for its spare battery pack, as shown and described.

DESCRIPTION

FIG. 1 is a front, top and right side perspective view of a charger stand for a portable handset telephone, and its spare battery pack;

FIG. 2 is a left side elevational view thereof;

FIG. 3 is a rear elevational view thereof;

FIG. 4 is a bottom plan view thereof; and

FIG. 5 is a bracket associated front, and top and right side perspective view of the spare pack spaced in front of the stand, and a front, top and right side of the charger stand with the spare pack shown removed.

*Fig. 1.**Fig. 2.**Fig. 3.*

Fig. 4.
